US0D1045489S

(12) **United States Design Patent** (10) **Patent No.:** **US D1,045,489 S**
(45) **Date of Patent:** **** Oct. 8, 2024**

(54) **COOKING POT**

(71) Applicant: **Fissler GmbH**, Idar-Oberstein (DE)

(72) Inventors: **Tim Konetzka**, Augsburg (DE);
Hyung-Chul Kim, Yongin-si (KR);
Karsten Kuber, Offenbach (DE)

(73) Assignee: **Fissler GmbH**, Idar-Oberstein (DE)

(**) Term: **15 Years**

(21) Appl. No.: **29/795,542**

(22) Filed: **Jun. 18, 2021**

Related U.S. Application Data

(62) Division of application No. 35/508,828, filed on Sep. 10, 2019 (U.S. filing date under 35 U.S.C. 384), and having an international filing date of Sep. 10, 2019, now Pat. No. Des. 925,976.

(57) **CLAIM**

The ornamental design for a cooking pot as shown and described.

DESCRIPTION

FIG. 1 is a perspective view of the cooking pot of one embodiment of the claimed design;

FIG. 2 is a top plan view of the cooking pot shown in FIG. 1;

FIG. 3 is a front elevational view of the cooking pot shown in FIG. 1;

FIG. 4 is a back elevational view of the cooking pot shown in FIG. 1;

FIG. 5 is a left side elevational view of the cooking pot shown in FIG. 1;

FIG. 6 is a right side elevational view of the cooking pot shown in FIG. 1; and,

FIG. 7 is a bottom plan view of the cooking pot shown in FIG. 1.

In FIGS. 1-7, the ornamental design which is claimed is shown in solid lines in the drawings. The broken lines in the drawings are for illustrative purposes only and form no part of the claimed design.

1 Claim, 7 Drawing Sheets
